UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

TRANSOM-OPERATOR.

1,306,292.

Specification of Letters Patent. Patented June 10, 1919.

Application filed November 3, 1916. Serial No. 129,351.

To all whom it may concern:

Be it known that I, HENRY G. VOIGHT, a citizen of the United States, residing in New Britain, county of Hartford, and State 5 of Connecticut, have invented certain new and useful Improvements in Transom-Operators, of which the following is a full, clear, and exact description.

This invention relates to transom operators, and the primary object of the invention is to provide a very simple, efficient transom operator of the concealed type, which can be very cheaply produced.

Another object of the invention is to provide a transom operator in which the operating means may be very readily manipulated, said operating means including, nevertheless, certain instrumentalities for locking the transom firmly in the fully opened position, as well as in the closed position.

A still further object of the invention is the provision of a transom operator in which the transom when released from the open position in which it is locked is returned 25 automatically to the closed position by a spring, and in which the effect of this spring can be controlled as desired.

To these and other ends, the invention consists in the novel features and combinations of parts to be hereinafter described and claimed.

In the accompanying drawings,

Figure 1 is a front elevation of a portion of a door frame and transom to which my 35 improvements are applied;

Fig. 2 is a fragmentary front elevation on a larger scale, with certain parts omitted;

Figs. 3 and 4 are elevations of the parts shown in Fig. 2, showing the transom in the 40 closed and open positions respectively;

Fig. 4^a is a front elevation of certain parts shown in Fig. 2, said parts being in the position corresponding to the open position of the transom; and

45 Figs. 5 and 6 are fragmentary side elevations of a transom operator of somewhat modified form.

In the form shown, the transom 10 of usual construction is located in the upper 50 part of a door frame in the customary manner, and the transom operating means is housed for the most part in the door casing 11. This operating means includes a flat base plate 12, which may be conveniently

attached to the inside of the door casing 55 by screws 13. This plate is relatively short, extending from a point slightly above the lower edge of the transom to a point not very far below the lower edge of the transom. Near its upper end, the plate carries 60 a journal block 14, which serves as a bearing for a rock shaft 15, by means of which the transom is manipulated. This rock shaft extends through an opening in the casing, and carries at its inner end a crank 65 or arm 16, secured to the edge of the transom. Preferably, the arm 16 is mortised in the edge of the transom and secured in place by screws 17. It will be understood that by the construction described, the shaft 15 70 forms in effect a swinging trunnion fixed to the transom, and operating in an opening in the door frame at one side of the transom. At the opposite side, the transom is swingingly supported in the door frame 75 by a plain trunnion and socket, which I have not considered it necessary to illustrate. The shaft 15 and the transom carried thereby are operated by means of a depending swinging arm 18. In the particular embodiment shown, the outer end of the shaft is of square cross section, and the upper end of the arm 18 has a square opening conforming to the square portion of the shaft beneath a cotter pin 19, so that the shaft 85 and arm are effectively interlocked. The mechanism for operating the arm 18 includes a sliding bar 20, adapted to move in a substantially vertical direction when actuated by a crank 21 or the like, accessible 90 at the outside of the door casing. The upper end of the slide 20 is pivoted at 22 to a bell crank or elbow lever 23, pivotally mounted at the bend of its elbow on the base plate by means of a pivot member 24. At 95 its other end, the lever 23 is pivoted at 25 to a short link 26 at one end of said link, the opposite end of said link being pivoted at 27 to the lower end of the operating arm 18.

At the lower end of the slide 20, the same is operatively connected with the crank 21. This crank, which has a suitable knob by means of which it may be turned manually, is mounted on the forward end of a rock 105 shaft 28, which in the form shown, is journaled in a U-shaped bracket 29 secured to the base plate by screws 30 at a point imme-

diately behind the inner casing member of the door frame. The shaft 28 extends horizontally in a forward and rearward direction relatively to the door, *i. e.*, in a plane 5 parallel to the base plate and perpendicular to the plane of the door frame. At its inner end, this rock shaft is provided with a crank portion 31, to which is pivoted at 32 a curved link 33. In the form shown, one end of 10 the link 33 fits between ears 34 on the crank portion 31, and the opposite end of the link fits between ears 35 on the lower end of the slide 20, between which ears 35 the link is pivoted by a pivot member 36. 15 It will be understood that by the connections described, the slide 20 may be raised and lowered by rotation of the hand crank 21.

In order to provide convenient means for 20 limiting the outward movement of the transom, I provide a pin 18^a projecting from the base plate 12 with which the lever 18 contacts, as shown in Fig. 4.

A spring 37 normally holds the transom 25 in the closed position. In the particular form shown, this spring is of the helical type, and it is connected at one end with the slide 20, (at 38), and at the opposite end with the base plate. In order that the 30 spring may be adjusted as required, this connection with the base plate comprises a post 39 on the base plate, on which is rotatable a small ratchet wheel 40, cooperating with a pivoted pawl 41 on the base plate. 35 The spring is connected with the ratchet wheel at one point in the periphery of said wheel, as shown at 42. The spring exerts a downward pressure on the slide, tending to hold the transom in the closed position, 40 as shown in Fig. 3. When the pawl and ratchet are in the adjustment shown in this figure, the point of connection 42 of the spring with the ratchet wheel is in line with the points 38, 39, and the spring is 45 therefore of minimum length and under minimum tension. In order to put further tension on the spring, which may be necessary in some cases to hold the transom firmly shut, the ratchet may be rotated to 50 lengthen the spring in an obvious manner, and the pawl will then hold the ratchet in the position to which it is adjusted.

The operation of the device will be fairly 55 obvious from the foregoing description. In the closed position of the transom, the latter is firmly locked in place owing to the fact that the toggle connection between the arm 18 and the slide 20, including the levers 23, 26 is in a locking position. In this position, the pivots 24, 25 and 27 are all in line with each other. The elbow lever 23 rests against a stop 28^a on the base plate, so that the levers are held on a dead center. The spring 37 acting on the slide 20 holds the 60 parts in the positions indicated, and it is 65

impossible for the transom to be jarred out of its closed position, inasmuch as the toggle lock cannot be accidentally "broken" or released. When it is desired to open the transom, however, the hand crank 21 is rotated through one hundred and eighty degrees, from the position shown in Fig. 3 to the position shown in Fig. 4. In this operation, the crank 31 on the inner end of the shaft 28 is raised, thereby lifting the 75 slide through the link 33. As the slide is shifted upwardly against the tension of the spring 37, the levers 23, 26 and the arm 18 and transom assume the positions shown in Fig. 4. When the transom reaches a definite open position, the crank 31 and link 33 line up with each other, so that the points 32, 36 are in line with the shaft 28. The crank 31 and link 33 therefore form a 80 toggle connection which locks the transom in the open position, both pivots of the link 33 being in substantial vertical alinement with the operating shaft 28. In order that the transom may be effectively held in the open position, the pivot 32 passes the dead 85 center line to a very slight extent, and it will be understood that under these circumstances, the spring 37 tends to hold the parts in the locked position. When it is desired to close the transom, however, a slight 90 movement of the hand crank 21 will break the toggle connection 31, 33, and the spring 37 will then immediately return the parts to the initial position in which the transom 95 is closed.

In the modification shown, in Figs. 5 and 6, the toggle lock mechanism between the manual operating device and the operating slide is of somewhat different construction. Here the lower end of the slide 20 is guided 100 in a clip 20^a, and is pivoted at 42 to a link 43, which in turn is pivoted at 44 to an arm 45 mounted on a stud 46 on the base plate. The arm 45 is operated by a hand lever or arm 47 projecting through the inner casing member and movable in a plane parallel to the base plate. When the transom is 105 in the closed position, the arm 45 and link 43 occupy the position shown in Fig. 5, the operating handle 47 being raised. When this handle is lowered, by turning it on the axis of the stud 46, the inner end of the arm 45 is raised, and this arm through the link 43 lifts the slide to open the transom. When the transom has been opened to a certain 110 definite extent, the toggle members 43, 45 move into substantial alinement, as shown in Fig. 6, so as to lock the transom in the open position.

Various changes may be made in the details of the construction without departing from the scope of the invention as defined in the claims.

What I claim is:

1. In a transom operator, the combination

tion of a transom, a swinging operating member rigidly secured to the transom, a slide movable up and down, means for operating said slide, a toggle connection between said slide and said swinging member, and a toggle connection between said slide and said operating means, said first toggle connection adapted to lock the transom in the closed position and said second toggle connection adapted to lock the transom in the open position.

2. In a transom operator, the combination of a base plate, a swinging operating arm having a swivel mounting therein, a slide mounted on the face of said base plate to move in a substantially vertical direction, a toggle connection between said slide and said operating arm whereby said transom is locked in the closed position, an operating

member for said slide, and a toggle connection between said slide and said last named member which raises the slide to open the transom and holds the transom in the open position.

3. In a transom operator, the combination of a transom, an operating slide therefor, a toggle operatively connecting said slide and transom, a second toggle for operating said slide, a casing inclosing the slide and toggles, and means extending through said casing for operating said second toggle comprising a manually operable rocking shaft directly connected to one arm of said last mentioned toggle, the other arm of the toggle connected to said slide.

In witness whereof, I have hereunto set my hand on the 30th day of October, 1916.

HENRY G. VOIGHT.
